UNITED STATES PATENT OFFICE.

CHARLES W. JONES, OF CHARLOTTE, NORTH CAROLINA.

BRICK AND BLOCK MOLD.

No. 925,703.

Specification of Letters Patent.

Patented June 22, 1909.

Application filed August 7, 1908. Serial No. 447,438.

To all whom it may concern:

Be it known that I, CHARLES W. JONES, a citizen of the United States, residing at Charlotte, in the county of Mecklenburg and State of North Carolina, have invented a new and useful Brick and Block Mold, of which the following is a specification.

This invention relates to molds for making artificial stone bricks or blocks of that general class shown and described in United States Letters Patent issued to me on the 12th day of May 1908 under No. 887,398.

The object of the invention is to improve and simplify the construction of the mold and to so arrange the core members as to permit removal of the same from the top of the mold, thereby leaving the bricks or blocks resting closed end down on the pallet.

A further object of the invention is to provide a mold having a core formed of a plurality of sections separated by division plates to form independent molding compartments.

A further object is to provide means for clamping the core members in engagement with the division plates, and means for releasing said plates thereby to permit removal of the molded product.

A still further object of the invention is generally to improve this class of devices so as to increase their utility, durability and efficiency.

Further objects and advantages will appear in the following description, it being understood that various changes in form, proportions and minor details of construction may be resorted to within the scope of the appended claims.

In the accompanying drawings forming a part of this specification: Figure 1 is a perspective view of a brick or block mold constructed in accordance with my invention, a portion of the side walls and division plates being broken away to more clearly show the construction of the same. Fig. 2 is a detail longitudinal sectional view. Fig. 3 is a top plan view of a portion of the mold showing the spacing members in closed or operative position. Fig. 4 is a similar view showing the spacing members in extended or operative position. Fig. 5 is a transverse sectional view. Fig. 6 is a detail perspective view of one of the spacing members detached. Fig. 7 is a detail perspective view of a portion of the brick facing plate.

Similar numerals of reference indicate

corresponding parts in all of the figures of the drawings.

The improved mold forming the subject matter of the present invention includes a pallet 5 on which are mounted vertically disposed end pieces 6 having transverse slots 7 formed therein and spaced from the lower longitudinal edges of the end pieces, as shown.

Interposed between the end pieces 6 is a core member formed of a plurality of separate sections 9 each preferably stamped or otherwise formed from a single sheet of metal having its opposite ends bent to produce terminal beads 10 adapted to receive a connecting rod or wire 11. The opposite edges of the core sections 9 are cut away to produce shoulders 12 which bear against corresponding shoulders 13 formed in the division plates 14. The division plates 14 are spaced apart by the core sections 9 to form independent molding compartments 15 conforming to the shape of the core sections, thereby to produce a substantially U shaped block.

A pair of division plates 14 are arranged at the juncture of adjacent core sections and interposed between said plate are co-acting wedge shaped spacing members 16 preferably extending the entire height of the plates 14 and having their lower edges resting on the pallet 5. Each spacing member or block 16 is provided with a vertical extension 17 adapted to bear against the exterior walls of the adjacent core sections, said spacing members being formed with longitudinally disposed slots 18 arranged in horizontal alignment with each other and each having one wall thereof formed with a series of teeth constituting a rack 19.

Disposed longitudinally of the mold and extending through the several core sections are spaced longitudinally movable actuating rods 20 having openings formed therein for the reception of clamping pins 21, which latter are arranged to bear against the adjacent division plates 14 for the purpose hereinafter referred to.

Slidably mounted between the actuating rods 20 is an auxiliary actuating rod 22 also provided with vertically disposed pins 23 similar in construction to the pins 21.

The clamping pins or members 21 of the actuating rods 20 are arranged to bear against one of the division plates of each

set, while the pins 23 of the auxiliary actuating rod 23 are arranged to bear against the mating plate of said set, thereby to clamp said division plates in engagement with said spacing blocks and thus support the core members and their associated parts in assembled position during the molding operation.

The actuating rods 20 are formed with gear teeth 24 which engage the teeth of the racks 19 and serve to move the spacing blocks to operative and inoperative positions when said actuating rods are rotated, there being hand operated levers 25 depending from the forward ends of the actuating rods 20 for rotating said rods to effect the movement of the wedge shaped spacing blocks.

Pivotaly mounted at 26 on the forward end of the auxiliary actuating rod 22 is a pair of levers 27 having their intermediate portions extended between spaced collars 28 on the actuating rods 20 and pivotally mounted at 29 on said rods, as shown. The free ends of the levers 27 are extended longitudinally beyond the pivot points 29 so that by moving the free ends of the levers 27 in the direction of the arrow indicated in Fig. 1 of the drawings, the actuating rods 20 will be moved longitudinally of the mold in the direction of the front end thereof so as to release the pins 21 from engagement with the adjacent spacing plates, while the central or auxiliary rod 22 will be moved in the opposite direction so as to move the clamping pins 23 out of engagement with the mating division plates. When the levers 27 are moved in the direction of the rear end of the mold the clamping pins on the main and auxiliary actuating rods 20 and 22 will be moved toward each other thus bringing the mating plates of each set together so as to separate the same from the cement or concrete constituting the body of the block and thus permit the ready removal of the latter.

The intermediate portions of the division plates are formed with suitable openings for the reception of the main and auxiliary actuating rods, while the upper edges thereof are provided with vertical recesses 30 so as to permit the core sections to be readily positioned in the mold with the shoulders 12 bearing against the shoulders 13 on said division plates.

Extending transversely across the main and auxiliary actuating rods is a bar 31 having a depending pin 32 which travels in an elongated slot 33 formed in the central rod 22, the opposite ends of the bar 31 being connected with the actuating rods 20 and extended longitudinally beyond said rods to form supports for locking devices 34. The locking devices 34 are preferably in the form of levers having their intermediate portions pivotally mounted at 35 on the extended ends of the bar 31 and their inner ends pro-

vided with cam faces 36 adapted to bear against the adjacent end pieces 6 for clamping the core sections and division plates in assembled position.

Extending longitudinally of the mold and bearing against the opposite ends of the division plates 14 are side strips 37 which engage the end pieces 6 and constitute the side walls of the molding compartments.

In operation the hand cranks 25 are rotated so as to cause the gears on the actuating rods to engage the racks on the spacing plates and move the latter to operative position between the division plates. The levers 27 are then moved toward the rear of the mold which causes the clamping pins on the main and auxiliary rods to engage the adjacent division plates and clamp the latter in engagement with the spacing members. The locking members 34 are then actuated to clamp the division plates and core members in assembled position, after which the cement, concrete or other plastic material is introduced within the molding compartments 15. After the cement in the molding compartments has set the locking members or cams 31 are moved to released position and the cranks 25 rotated to withdraw the spacing members 16 from between the division plates, after which the levers 27 are moved toward the rear end of the mold which presses the division plates together and thus prevents the same from adhering to the cement constituting the body of the block. When the division plates have been drawn together the mold is lifted bodily from the pallet thus leaving the molded bricks or blocks resting closed end down on said pallet and in which position they may be readily carried to the drying racks without danger of breakage.

In order to form the bricks or blocks with an ornamental or finished surface there is provided a plurality of longitudinally adjustable plates 39 arranged in over-lapped relation and provided with depending extensions 40 adapted to fit between the walls of the adjacent molding compartment 15, the sets of over-lapped plates being spaced apart to form an auxiliary compartment 41 for the reception of relatively fine material constituting the exposed face of the block. The upper edges of the plates 39 are provided with laterally extending wings 42 which constitute in effect a hopper and serve to direct the material into the auxiliary compartment 41.

In using the facing attachment shown in Fig. 7 the extensions 40 are introduced within the compartments and said extensions adjusted longitudinally so as to close the outer ends of the main molding compartment and produce the auxiliary molding compartment 41, said extensions being fastened in adjusted position by a locking member 42'. One end of the locking member 42' is pivot-

ally mounted on one of the plates 39, while the opposite end thereof is provided with a series of notches 43 adapted to engage a pin 44 extending laterally from the adjacent plate 39. When the facing attachment is fastened in position in the manner described, the main compartment is filled with relatively coarse material, while the auxiliary compartment is filled with fine sand and cement so as to give the exterior face of the block a neat finished appearance.

It will here be noted that by moving the spacing members 16 laterally and inserting longer division plates the capacity of the molding compartments may be varied so as to permit the formation of bricks or blocks of different sizes.

A suitable deflector 45 is arranged above the several core sections for deflecting the cement or concrete into the molding compartments.

The molds may be made in different sizes and shapes and several of said molds arranged side by side, in which event, each set of molds will be provided with a deflector for directing the material into the adjacent compartments.

From the foregoing description, it is thought that the construction and operation of the devices will be readily understood by those skilled in the art and further description thereof is deemed unnecessary.

Having thus described the invention what is claimed is:

1. A mold including a sectional core, division plates interposed between the core sections and defining molding compartments, overlapping members interposed between adjacent division plates, means for clamping the division plates in engagement with the core sections, and means for releasing said plates.

2. A mold including a sectional core, spaced plates extending transversely of the core between said sections and defining molding compartments, overlapping wedge shaped spacing members interposed between the division plates, means for moving the spacing members to operative and inoperative positions, and means for drawing the division plates toward each other when the spacing members are in inoperative position.

3. A mold including a sectional core, a pair of division plates disposed at the juncture of adjacent core sections and defining molding compartments, overlapping wedge shaped spacing members interposed between the division blocks, means extending longitudinally of the mold and co-acting with the spacing members for moving the latter to operative and inoperative position, means for clamping the division plates in engagement with the spacing members, and means for drawing the division plates toward each

other when the spacing members are in in- 65 operative position.

4. A mold including a sectional core having division plates interposed between each core and defining intermediate molding compartments, over-lapping wedge shaped spacing members interposed between adjacent division plates, means co-acting with the spacing members for moving the latter to operative and inoperative positions, and means for drawing the spacing plates toward 75 each other when the spacing members are moved to inoperative position.

5. A mold including a sectional core, spaced division plates disposed at the juncture of adjacent cores, wedge shaped spacing 80 members interposed between adjacent division plates and provided with racks, actuating rods having gear teeth adapted to mesh with the racks for moving the spacing members to operative and inoperative positions, 85 and means for drawing the division plates together when the spacing members are moved to inoperative position.

6. A mold including a plurality of U-shaped core sections, division plates disposed 90 at the juncture of adjacent core sections, spacing members interposed between adjacent division plates and provided with racks, longitudinally movable actuating rods having gears adapted to mesh with the teeth on 95 the racks for moving the spacing members to operative and inoperative positions, means carried by the actuating rods for clamping the plates in engagement with the spacing members, said clamping means also serving 100 to draw the division plates toward each other when the spacing members are moved to inoperative position.

7. A mold including a plurality of substantially U shaped cores, spaced division plates 105 disposed at the juncture of the adjacent cores, and defining intermediate molding compartments, there being slots formed in the spacing members, the walls of which are provided with teeth constituting racks, longitudinally movable actuating rods provided with gears adapted to engage the teeth on the racks for moving the spacing plates to operative and inoperative positions, pins carried by the actuating rods for clamping the 110 division plates in engagement with the spacing members, and means for rotating the actuating rods to effect the movement of the spacing members.

8. A mold including a plurality of core 120 sections, spaced division plates disposed at the juncture of adjacent core sections and defining molding compartments, spacing members interposed between the division plates, racks carried by the spacing members, primary actuating rods provided with gears adapted to mesh with the teeth on the rack for moving the spacing members to op-

- erative and inoperative positions, pins carried by the primary actuating rod and adapted to engage the adjacent division plates for clamping the latter in engagement with the 5 spacing members, an auxiliary actuating rod provided with corresponding pins coöperating with the pins on the primary rod, and means for rotating the primary rods to effect the movement of the spacing members.
- 10 9. A mold including a plurality of independent core sections, division plates disposed at the juncture of adjacent core sections, over-lapping spacing members interposed between the division plates and provided with 15 racks, longitudinally movable actuating rods having gears arranged to mesh with the teeth of the racks, an auxiliary actuating rod, said primary and auxiliary actuating rods being provided with pins adapted to engage the division plates for clamping the latter in engagement with the spacing members, and levers pivotally connected with the main and auxiliary actuating rods for moving the pins to operative and inoperative positions.
- 20 10. A mold including a plurality of core sections, spaced division plates disposed at the juncture of the adjacent core sections and defining intermediate molding compartments, spacing members interposed between adjacent plates and provided with 25 racks, primary actuating rods provided with teeth for engagement with the racks on the spacing members, an auxiliary actuating rod, pins carried by the main and auxiliary 30 actuating rods and adapted to bear against the division plates for clamping the latter in engagement with the spacing members, levers pivotally connected with the main and auxiliary rods for actuating the same, a bar 35 extending transversely across said rods, cams pivotally mounted on the ends of the bars and adapted to bear against the adjacent wall of the mold, and means for rotating the main actuating rod to effect the movement 40 of the spacing members.
- 45 11. A mold including a pallet, end pieces resting on the pallet, a plurality of U shaped core sections supported between the end pieces, spaced division plates disposed at the 50 juncture of adjacent core members and resting on the pallet, over-lapping wedge shaped spacing members interposed between adjacent division plates and provided with racks, main and auxiliary actuating rods having 55 pins for engagement with the division plate for clamping the latter against the spacing members, means carried by the main actuating rod and engaging the spacing members for moving the latter to operative and inoper- 60 ative positions, side walls bearing against the opposite ends of the division plates, a bar connecting the main and auxiliary actuating rods, and locking members pivotally mounted on the bar and adapted to bear against the 65 adjacent end piece.
12. A mold including a pallet, end pieces supported on the pallet, a plurality of core sections having their opposite edges provided with shoulders, spaced division plates disposed at the juncture of adjacent core sections and provided with corresponding shoulders for engagement with the shoulders on said core sections, spacing members interposed between the division plates and provided with racks, main actuating rods slidably mounted in the division plates and provided with gears adapted to engage the racks for moving the spacing members to operative and inoperative positions, side walls supported by the pallet and bearing against the 70 ends of the spacing members, cranks secured to the main actuating rods for rotating the latter to effect the movement of the spacing members, pins carried by the actuating rods, an auxiliary actuating rod provided with corresponding pins, and levers forming a pivotal connection between the main and auxiliary actuating rods for operating the pins to clamp the division plates in engagement with the spacing members. 75
13. A mold including a core formed of a plurality of substantially U shaped sections having their opposite ends bent to form reinforcing beads, rods extending through the beads of the several core sections, division 80 plates interposed between adjacent core sections, laterally movable overlapping wedge shaped spacing members operating between the division plates, means for clamping the core members in engagement with the division plates, means for moving the spacing members to operative and inoperative positions, and means for drawing the division plates together when the spacing members 85 are moved to inoperative position. 90
14. A mold including a pallet, a sectional core suspended within the mold and spaced upward from the bottom of the pallet, division plates interposed between adjacent core sections, laterally movable spacing members 95 operating between the division plates, side walls bearing against the opposite ends of the division plates, end walls engaging adjacent core sections, means extending longitudinally through the core sections for clamping the division plates in engagement with the spacing members, means operatively connected with the plate moving means for actuating the spacing members, said plate 100 operating means also serving to draw the division plates together when the spacing members are moved to inoperative position. 105
15. In testimony that I claim the foregoing as my own, I have hereto affixed my signature in the presence of two witnesses.
